UNITED STATES PATENT OFFICE.

JULIAN F. BENJAMIN, OF NEW ORLEANS, LOUISIANA.

DESIGN FOR A CHILD'S VEHICLE OR SIMILAR ARTICLE.

57,304.

Specification for Design.

Patented Mar. 15, 1921.

Application filed December 29, 1919. Serial No. 348,187. Term of patent 3½ years.

To all whom it may concern:

Be it known that I, JULIAN F. BENJAMIN, a citizen of the United States, residing at New Orleans, in the parish of Orleans and State of Louisiana, have invented a new, original, and ornamental Design for a Child's Vehicle or Similar Article, of which the following is a specification.

The accompanying drawing is a perspective view of a child's vehicle or similar article embodying the design.

I claim:

The ornamental design for a child's vehicle, or similar article as shown.

JULIAN F. BENJAMIN.
